United States Patent Office.

DESIGN FOR A TRADE MARK.

DANIEL B. KIMBALL, OF NEW YORK, N. Y.

Design No. 2,527, dated December 11, 1866.

The Schedule referred to in these Letters Patent and making part of the same.

TO ALL WHOM IT MAY CONCERN:

Be it known that I, DANIEL B. KIMBALL, of the city and State of New York, have originated and designed a new Design for a Trade Mark; of which the following is a full, clear, and exact description, reference being had to the accompanying drawings, making part of this specification.

The design consists of the words—English Metallic Roofing Paint, D. B. KIMBALL, Sole Proprietor, New York—arranged in the form and manner shown in the drawings.

What I claim as my invention, and desire to secure by Letters Patent, is—

The design for a trade mark herein set forth and shown.

DANIEL B. KIMBALL.
